DISPENSER CARTON HOLDER

Frank L. Broeren, Neenah, and Archie S. Krueger,
Green Bay, Wis., assignors to Marathon Paper
Mills Company, Rothschild, Wis., a corporation
of Wisconsin

Application December 16, 1940, Serial No. 370,415

5 Claims. (Cl. 312—62)

This invention relates to a holder for a dispensing carton.

One of the objects of this invention is to provide an inexpensive and simple support and holder for a carton having dispensing openings therein for withdrawal of one sheet at a time from a stack of sheets contained within the carton.

A further object of this invention is to provide a holder for a dispensing carton, said holder being provided with means for snugly retaining a carton supported thereon and also being provided with spring means adapted to be inserted within the carton while supported on the holder for suitably positioning the sheets contained within the carton in proper dispensing position.

A further object of this invention is to provide a combination dispensing carton and holder whereby a simple and inexpensive means are provided for retaining a stack of interfolded sheets within a carton and supporting said carton on the holder while the sheets are dispensed therefrom one at a time.

Other further objects of the invention will be apparent from the following specification and drawings.

Referring to the drawings:

Figure 1 is a perspective view of the holder and support for the carton, the carton being shown in elevated position above the support in partially fragmental condition.

Figure 2 is a plan view of the bottom side of the carton holder showing the carton on the bottom of the holder.

Figure 3 is a top plan view of the support without the carton thereon.

Figure 4 is a view taken on lines 4—4 of Figure 2.

Figure 5 is an enlarged fragmental sectional view taken on lines 5—5 of Figure 3.

Referring to the drawings wherein like numerals indicate similar parts, the holder for the carton is indicated generally by the letter "A" and the carton to be supported thereon is indicated generally by numeral 1. The support or carton holder is preferably made from sheet metal and consists of a flat base 16 and inclined faces 10 integral therewith. At each end of the base 16 upwardly extending end brackets 11 are provided having side flange portions 14 and 15 which are adapted to engage snugly the ends of the carton 1 retained in the holder. Side brackets 17 are also provided at each side of the base extending upwardly for snugly engaging the sides of the carton 1. The upper portions of the brackets 17 are bent outwardly to form flange portions

18. These upwardly extending side brackets 17 and end brackets 11 and 12 serve to retain the carton on the holder. Extending upwardly and affixed to the bottom 16 is a vertical supporting member 20 which is provided with a slot 49 at its upper portion for receiving and retaining a bent generally U-shaped spring member designated by numerals 21 and 22. The spring member is secured to the support by means of a rivet 50 and in order to prevent any lateral displacement crimps or corrugations 51 are formed in the support to retain the upper U-portion 52 of the spring in fixed position. The lower free end portions 61 and 62 of the spring extend downwardly toward the base member 16 and are bent inwardly toward each other and in offset relation as illustrated in Figures 3 and 4 of the drawings. By bending and curving the lower ends of the spring member, a greater resilient action of the free ends of the spring is secured when positioned within the carton as illustrated in Figure 4 of the drawings. It will also be noted that portions 5 adjacent free ends of the spring are flattened to make face contact with the sheets in the carton. Lower portions of the spring members are adapted to exert a pushing force against each portion of the divided stack of interfolded sheets 40 within the carton and as the sheets are withdrawn through the dispensing openings on each face of the carton, the stack portions are urged forwardly toward each of the dispensing openings as indicated by the dotted lines in Figure 4.

The dispenser is advantageously provided with vacuum cups 25 in each lower corner thereof so that the holder can be positioned upon a table or any other support and firmly retained thereon by the vacuum action of the cups. In this manner the holder will not slip around when the sheets are individually pulled from the dispensing openings in the carton.

The type of carton which is adapted to be supported upon the holder is constructed preferably of cardboard and the like and has a front wall 7 and rear wall 8 each provided with a dispensing opening 9 for withdrawing the foremost sheet 40 from the stack retained therein. The dispensing openings 9 are provided with hinged closure panel portions 31 and 32 adjacent the openings in order to assist in guiding the sheets as they are withdrawn from the carton, and also for closing the opening when the carton is not in use or for shipping purposes in order to protect the contents. The bottom 70 of the carton is provided with a slit 71 which is adapted to

permit insertion of the support 20 and the spring members 21 and 22 when the carton is positioned on the holder.

The cartons 1 are usually supplied to the consumer and are adapted to be used only once and after the sheets are completely withdrawn therefrom are discarded. The carton, thus serves as a convenient package for shipping the interfolded sheets to the consumer who is provided with the holder as illustrated in Figure 1.

The carton 1 is positioned as illustrated in Figure 1 and slipped over the supporting member 20 and the spring members 21 and 22 retained thereon so that they are inserted within the carton. Owing to the flexibility of the members 21 and 22, they will be bent toward each other sufficiently to permit insertion within the stack of interfolded sheets 40', contained in the carton in the position illustrated in Figure 4 of the drawings. The lower hinged closure panels 32 of the carton are then folded outwardly and supported upon the outwardly bent flange members 18 as illustrated in Figure 4 and the upper closure panels 31 are folded to extend outwardly of the carton as also shown in Figure 4 to provide dispensing openings 9. The sheets 40' are withdrawn one at a time from either of the dispensing openings in the opposite sides of the carton 1 and as they are withdrawn, the springs 21 and 22 will urge the divided stack of sheets toward the front of the dispensing openings within the carton in proper position for grasping of the foremost sheet therefrom.

The carton 1 is manufactured of such dimensions that it will be snugly received and retained upon the support 20, the bottom 70 resting on the bottom 16 of the holder and the end brackets 11 with side flanges 14 and 15 snugly engaging the ends of the carton and the side brackets 17 engaging the front panel 7 and rear panel 8 of the carton. The carton will thus be retained not only by frictional engagement of the bracket members on the support but also by the spring contained within the carton proper. As the sheets are withdrawn one at a time therefrom, the carton will not be displaced or removed from the holder during dispensing operation. The vacuum cups 25 also serve to securely hold the support upon the table, counter, or other place upon which it may be used.

It will thus be evident from the foregoing description that a very simple and inexpensive and efficient holder for a dispensing carton is provided by this invention. The operation is exceedingly simple, there are no moving parts except for the spring action, and a minimum of mechanism is required to operate same. The carton holder can be constructed at a very low cost and distributed to the consumer who will thereupon only have to secure a new supply of cartons containing the interfolded sheets therein. The carton is adapted to contain interfolded sheets of waxed paper, paper towels, napkins, or any other suitable sheet material which it is desired to be dispensed from such a carton. A carton having the foregoing construction when retained upon the holder forms a very convenient combination for dispensing the sheets one at a time from the carton.

It is obvious that numerous modifications and changes may be made in the construction of both

the carton and the holder, and it is intended to include all such modifications and changes within the scope of the appended claims.

We claim:

1. A support for a removable dispensing carton having dispensing openings, an opening in the bottom wall and containing a stack of interfolded sheets, comprising a base, spring members supported upon said base, said spring members being adapted to be inserted within said carton through the opening in the bottom wall of said carton for dividing the said stack of sheets and each spring member being adapted to urge a stack portion toward a dispensing opening.

2. A support for a removable dispensing carton having dispensing openings, an opening in the bottom wall and containing a stack of interfolded sheets, comprising a base, a support upon said base, a flexible spring member attached at its medial portion to the upper portion of said support and the free ends thereof extending toward said base, said spring ends being curved inwardly, said spring member being adapted to be inserted within said carton through the opening in the bottom wall of said carton for dividing the said stack of sheets and for urging each stack portion toward the respective dispensing openings.

3. A support for a removable dispensing carton having dispensing openings, an opening in the bottom wall and containing a stack of interfolded sheets, comprising a base, a support upon said base, a flexible spring member attached to the upper portion of said support and the free ends thereof extending toward the base in offset relation and bent inwardly toward each other, said spring member being adapted to be inserted within said carton through the opening in the bottom wall of said carton for dividing the said stack of sheets and for urging each stack portion toward the respective dispensing openings.

4. A support for a removable dispensing carton having dispensing openings, an opening in the bottom wall and containing a stack of interfolded sheets, comprising a base, bracket members extending upwardly from each end of said base for engaging the ends of said carton, side brackets extending upwardly from each side of said base for engaging the side walls of said carton, spring means supported upon said base, said spring means being adapted to be inserted within said carton through the opening in the bottom wall of said carton for dividing the said stack of sheets and for urging each stack portion toward the respective dispensing opening.

5. In combination, means for supporting and dispensing a stack of interfolded sheets comprising a carton having dispensing openings in opposite side walls of said carton for withdrawal of one sheet at a time therefrom, and an opening in the bottom wall; and a support for said carton comprising a base upon which the bottom of said carton is supported and spring means on said base adapted to be inserted into the carton through the opening of the bottom wall of said carton, said spring means being adapted to divide the said stack and to urge each stack portion toward the respective dispensing openings in said carton.
